DESIGN FOR A TELESCOPE SUPPORT

William Levin, New York, N. Y.

Application February 20, 1946, Serial No. 126,755

Term of patent 3½ years

(Cl. D57—1)

To all whom it may concern:

Be it known that I, William Levin, a citizen of the United States of America, residing in New York, county of Kings, and State of New York, have invented a new, original, and ornamental Design for a Telescope Support, of which the following is a specification, reference being had to the accompanying drawing, forming part thereof.

The figure on the drawing is a perspective view of a telescope support, showing my new design. The opposite side presents substantially the same appearance as the side shown.

I claim:

The ornamental design for a telescope support, substantially as shown and described.

WILLIAM LEVIN.
